C. C. EMICK

JAR CLOSURE

Filed Aug. 17, 1922

Larry, Larry, Attorneys

UNITED STATES PATENT OFFICE.

CHARLES C. EMICK, OF LANCASTER, PENNSYLVANIA.

JAR CLOSURE.

Application filed August 17, 1922. Serial No. 582,446.

To all whom it may concern:

Be it known that I, CHARLES C. EMICK, a citizen of the United States, residing at Lancaster, in the county of Lancaster and 5 State of Pennsylvania, have invented certain new and useful Improvements in Jar Closures, of which the following is a specification.

This invention relates to an improvement 10 in jar closures and more particularly to an improved closure for fruit jars of the well known Mason or Ball type.

One of the primary objects of the invention is to provide a jar closure of the above 15 mentioned type with a novel form of handle adapting the jar to be carried about from place to place in the most convenient manner. While jar closures of this type have heretofore been provided with handles, it 20 has been customary to connect the handle bail with ears soldered or otherwise secured on to the cap at diametrically opposite points but it has been found that this construction is not so desirable for the reason 25 that the ears are extremely liable to be broken off thus destroying the utility of the device. Therefore, the invention contemplates attaching the handle to the cap by a means much more substantial and durable 30 than the ears heretofore employed.

Another object of the invention is to provide in connection with the handle attaching means, a means adapted to assist in tightening the closure upon the jar and also 35 in removing the same, this means being not only produced in a most convenient manner as a part of the handle attaching means, but also serving the additional function of a rest for the wooden grip of the handle so 40 that the handle may be swung back or lowered to substantially horizontal position and will be supported in such position with its grip entirely out of contact with the jar. Therefore, the invention contemplates the 45 provision of means which will be of assistance in applying or removing the cap and which will serve also as a support for the handle member when the same is not in use.

50 In the accompanying drawings:

Figure 1 is a side elevation illustrating a jar closure or cap equipped with the improvements embodying the invention;

55 Figure 2 is a horizontal sectional view on the line 2—2 of Figure 1 looking in a downward direction;

Figure 3 is a perspective view of the handle member and its attaching means removed from the closure cap;

Figure 4 is a detail perspective view illustrating a modification of the invention.

In the drawings the numeral 1 indicates an ordinary fruit jar of the standard type provided with a neck 2 having the usual threads formed therein, the mouth of the jar being 60 closed by a closure cap 3 threaded on to the neck in the usual manner. The closure cap 3 is pressed or otherwise formed with the usual threads 4 which not only fit the threads upon the neck or mouth of the jar 65 but also serve an additional function which 70 will presently be explained.

The handle embodying the invention comprises an attaching member which is indicated in general by the numeral 5 and which is formed from a single length of wire bent to assume initially substantially the form of an open annulus. At a point diametrically opposite its open side the annular attaching member 5 is bent upon itself to provide a horizontally projecting finger piece indicated by the numeral 6. The said member 5 is disposed with its portions at opposite sides of the finger piece 6 seating in the grooves or valleys of the threads 4 of the cap, and the ends of said portions are preferably united to the cap by soldering or otherwise, and the said member is drawn tightly about the circumferential wall of the cap closure to snugly and firmly bind the same, and its end portions are soldered or otherwise suitably secured permanently to the cap at a point preferably diametrically opposite the point of location of the finger piece 6 as indicated by the numeral 7. The 90 side portions of the attaching member 5 are bent upon themselves to form upwardly laterally directed loops or ears 8, with which are pivotally engaged eyes 9 provided at the lower ends of the side members 10 of the handle proper, the said handle being indicated in general by the numeral 11 and comprising in addition to the members 10 a cross bail 12 upon which is rotatably mounted a preferably wooden hand grip 13. At 105 this point it will be understood that inasmuch as the annular attaching member 5 is seated in the valleys of the threads 4 which are presented at the outer surface of the circumferential wall of the cap, it is only necessary to unite the said member 5 to the cap closure by soldering its ends thereto, this

union being securely braced and reinforced by the engagement of the other portions of the said attaching member in the said valleys of the threads. Therefore, the threads 5 serve not only their primary function but they also serve as a seating or anchoring means for the member 5 and afford shoulders firmly bracing this member with relation to the said closure. In fact the arrangement 10 is a much more substantial one than that in which ears are soldered independently to opposite sides of the cap for engagement by the ends of the side members of the bail handle, and wherein such ears are extremely 15 liable to become distorted or torn loose.

The finger piece 6 constitutes a highly effective means by which force may be exerted in a direction circumferentially of the closure both for the purpose of fitting 20 it on to the mouth of the jar and also for the purpose of removing it and it will be evident that inasmuch as this finger piece is located at a point diametrically opposite the secured ends of the member 5, any strain 25 imposed upon the said soldered or otherwise secured ends of the member 5 will not be in a direction or manner tending to pry the ends of the member 5 loose from the cap closure but will rather be in the direction of 30 length or extent of the said end portions of the said member 5 and consequently a very considerable degree of force may be exerted against the finger piece 6 without any likelihood of distorting the member 5 or separating 35 the same from the closure. Preferably in forming the finger piece 6, the member 5 substantially midway between its ends is bent to form a substantially elliptical loop, and after this loop has been formed it is 40 preferably twisted at its juncture with the member 5 to occupy a substantially vertical plane as shown clearly in Figures 1 and 2 of the drawings. Not only does the finger piece 6 serve the purpose above explained, 45 namely as a medium whereby the cap closure may be securely tightened in place or conveniently removed from the jar, but it constitutes also a rest for the handle 11 when the handle is in swung down position for in 50 this position the grip 13 will rest upon the said finger piece 6. Thus if the jar is employed in preserving, the handle will be supported out of contact with the glass jar after the jars have been capped, and will not 55 be liable to become highly or uncomfortably heated as would be the case if it rested directly in contact with the jar. Furthermore, when the handle is lowered to position resting 60 upon the finger piece 6, it will occupy a substantially horizontal position and the upper side of its grip will be located approximately in the same plane as the upper side of the closure 3 so that it will in a sense 65 constitute an extension of said surface and thus enable the jars to be piled one on top of

another in a much more stable manner than if the handle were not present.

Figure 4 illustrates a slight modification of the invention in which the handle 11 is omitted, and the cap which is indicated by 70 the numeral 14, has applied and secured to it the ends of the arms 15 of a member embodying a finger piece indicated by the numeral 16 and corresponding to the finger piece 6. In this construction the arms 15 do not extend entirely about the cap 14 but only 75 part way around the same as it is unnecessary to provide the ears 8 if the handle is to be omitted.

It will be understood that not only does 80 the attaching member 5 serve the various purposes heretofore ascribed to it, but likewise it serves as a reinforcing means for the circumferential wall of the cap closure thus preventing spreading or other distortion of 85 this wall.

Having thus described the invention, what is claimed as new is:

1. The combination with a jar closure 90 having threads pressed in its circumferential wall, of a finger piece for the closure having portions extending in opposite directions therefrom circumferentially of said wall of the closure and seated and secured within the valleys of the threads. 95

2. The combination with a jar closure having threads pressed in its circumferential wall, of a substantially annular attaching member disposed to surround the closure and seated and secured within the valleys of the threads, and a handle bail pivotally connected with the said attaching member. 100

3. The combination with a jar closure having threads pressed in its circumferential wall, of a substantially open annular attaching member disposed to surround the closure and seat within the valleys of the threads and having its end portions secured in said valleys, the said attaching member being provided substantially opposite its said end portions with a finger piece against which pressure may be exerted to seat or unseat the closure. 105

4. The combination with a jar closure having threads pressed in its circumferential wall, of an open substantially annular attaching member disposed to surround the closure and seated within the valleys of the threads, the ends of the said member being secured within said valleys, the said member being formed with integral eyes located at diametrically opposite points and substantially equi-distantly spaced from the said attached ends of the member, and a handle bail connected at its sides with the said eyes. 115

5. The combination with a jar closure having threads pressed in its circumferential wall, of an open substantially annular attaching member disposed to surround the closure and seated within the valleys of the 120

threads, the ends of the said member being secured within said valleys, the said member being formed with integral eyes located at diametrically opposite points and substantially equi-distantly spaced from the said attached ends of the member, a handle bail connected at its sides with the said eyes, and

a finger piece formed by a bend in said attaching member located substantially diametrically opposite the secured ends of the member. 10

In testimony whereof I affix my signature.

CHARLES C. EMICK.
